UNITED STATES PATENT OFFICE.

MAX AMS, OF NEW YORK, N. Y.

DESIGN FOR A CRUET.

SPECIFICATION forming part of Design No. 16,066, dated May 5, 1885.
Application filed March 16, 1885. Term of patent $3\frac{1}{2}$ years.

To all whom it may concern:

Be it known that I, MAX AMS, of the city of New York, county and State of New York, have invented a new and original Design for 5 a Cruet, of which the following specification is a full, clear, and exact description, reference being had to the accompanying drawings, forming part thereof.

This invention relates to a novel design for 10 a cruet; and it consists in a cruet having a beaded base and three beaded compartments; also, in the paneling of the central compartment, all as hereinafter more fully pointed out.

15 In the accompanying drawings, Figure I is a side view of my newly-designed cruet. Fig. II is a top view of the same.

The letter A represents the base of the cruet, consisting of three circular sections, a 20 a' a'', tapering from the top downward. Upon the base is placed a bead, b, and above the bead project the rims of the three compart-

ments or chambers c c' c''. The central compartment, c', is higher and larger than the others, and is of cylindrical form. d is a top 25 bead, and e are upright panels which go to ornament the compartment c'.

The compartments c c'' are much lower than the compartment c', and are provided with concave sides f, as shown. 30

A bead, g, is formed on the top of compartments c c'.

I claim as my invention—

1. The design for a cruet, consisting of base A, compartments c c'', having bead g, and of 35 compartment c', having bead d and panels e, as described and shown.

2. The design for a cruet, consisting of base A, having bead b, and of compartments c c' c'', having beads d g, as described and shown. 40

MAX AMS.
